UNITED STATES PATENT OFFICE.

CHARLES P. TURNER AND WILLIAM T. DRAKE, OF HARRISBURG, AND JAMES E. LITTLE, OF STEELTON, PENNSYLVANIA.

ТИЛТИНГ ФУРНАС.

1,086,485.

Specification of Letters Patent.

Patented Feb. 10, 1914.

Application filed October 26, 1910. Serial No. 589,282.

To all whom it may concern:

Be it known that we, CHARLES P. TURNER and WILLIAM T. DRAKE, residing at Harrisburg, in the county of Dauphin and State 5 of Pennsylvania, and JAMES E. LITTLE, residing at Steelton, county and State aforesaid, have invented certain new and useful Improvements in Tilting Furnaces; and we do hereby declare the following to be a full, 10 clear, and exact description of the invention, such as will enable others skilled in the art to which it appertains to make and use the same, reference being had to the accompanying drawings, and to letters or figures of 15 reference marked thereon, which form a part of this specification.

This invention relates to tilting furnaces for use in the manufacture of iron and steel, and has for its object a structure that is 20 simple and effective, and readily operated, the structure of which will be hereinafter described, and particularly pointed out in the claims.

Referring to the drawings, in which like 25 parts are similarly designated Figure 1 is a vertical, central transverse section of the furnace. Fig. 2 is a detail side view of the door-operating mechanism. Fig. 3 is a vertical, central section of the lower part of the 30 furnace and the mechanism for effecting the tilting. Fig. 4 is a plan view showing the saddle and operating mechanism. Fig. 5 is a plan view of one of the rockers. Fig. 6 is an elevation thereof. Figs. 7, 8, 9 and 10 35 are sections on lines 7—7, 8—8, 9—9 and 10—10 of Fig. 6.

On a suitable masonry or other foundation A is secured a pedestal, formed for convenience of two castings 2 and 2^a. There 40 are as many of these pedestals as there are rockers, 3, provided for the furnace. The furnace illustrated has but two rockers, but any number may be used, as the size of the furnace may require or demand.

The pedestal is provided with two bearings 4 one in each portion 2 and 2^a of the pedestal. These bearings are substantially half bearings in which lie pins 5 supporting saddles 6 substantially triangular in 45 shape and having at one apex a substantially half bearing 7 that rests on the pin 5. At the other two apices of the triangular saddles 6 are mounted flanged bearing rollers 8. Each of the rockers 3 rests on the four 50 rollers 8 of two saddles 6, and the flanges 55

of these rollers prevent the rockers from slipping off sidewise. These saddles equalize the weight, have a slight rocking movement on the pins 5 and decrease the power required for tilting the furnace. 60

The rockers 3, shown in detail in Figs. 5 and 6, are castings made for convenience in two parts bolted together, one of which has a recess 9 into which fits a corresponding projection 10 on the other at their meeting 65 faces, said recess and projection assisting in holding the two parts in proper position relative to each other, and taking some of the strain off the bolts that bolt the two parts together to form a unitary rocker. The 70 rockers are provided with two openings 11, one in each of the two parts thereof, and through these openings and resting therein are passed girders or I-beams 12, preferably, but not necessarily, having plates 13 on the 75 top and bottom thereof, as shown in Figs. 3 and 4. Each rocker has a number of "pads" or supports for struts extending between the rockers and shown at 14 and 15, Figs. 6, 8 and 9, to which the struts are bolted. These 80 struts are composed preferably of rolled shapes, those secured to the pads 14 being I-beams 16 whose ends rest on the ledges 14^a Figs. 6 and 8.

Placed on the struts 16 and girders 12 85 crosswise and between the rockers are rolled shapes 17 on which are laid plates 18, forming part of the sheet metal casing of the furnace and on which the refractory walls of the furnace are built. The rockers 3 directly 90 support the furnace, i. e., the plates 18, but between the rockers these plates are supported by the I-beams 17. Connected to the underside of the struts 16 are plates 19, and similar plates 20 are connected to 95 and between the girders 12. The plates 19 and 20 are connected together by suitable means, herein shown as angles 21, and the plate or plates 20 are stiffened by similar angles 22. On the plate or plates 20 100 are secured one or more bearings 23. Two such bearings 23 are shown in the furnace illustrated, both being located between the rockers, see Fig. 4. These bearings carry pins 24 on whose ends projecting on each side 105 of the bearing 23, are mounted the ends of connecting rods 25. The opposite ends of each pair of connecting rods 25 are mounted on pins or stub-shafts 26 on a cross-head 27. The cross-head is mounted to slide on 110

guides 28 and is operated by a screw 29 passing through the cross-head. One end of each screw 29 is mounted in a fixed bearing 30 and the other in a roller thrust bearing 31 adjacent which latter is a gear wheel 32 keyed or otherwise fastened to the screw. The gear wheels 32 are driven by pinions 33 that are mounted on or driven from the rotor shafts of standard electric motors, not 10 shown.

Between the two pinions 33 and gearing with both of them is an idle gear wheel 34 mounted on a stub-shaft 35, the purpose of which is to equalize and synchronize the 15 speeds of the two wheels 32 and the screws to which they are attached. The wheel 34 is of the same size as the wheels 32. By operating the motors in one or the other direction the two screws 28 are simultaneously rotated, thereby traversing the cross-heads 27, which, by means of their connecting rods 25 rock or tilt the furnace either forward or backward to and from its horizontal position, and hold the furnace in any 20 of its positions within the limits of operation of the apparatus.

The furnace is provided with one or more openings 36, for the introduction of stock, the examination of the interior of the furnace etc. Each opening 36 is closed by a door 37 which opens by sliding upward in suitable ways 38 at the sides thereof. The door 37 is provided with a peep hole 39, and an eye 40, or other equivalent means, to 30 which is fastened a wire rope or chain. The furnace normally stands in the position shown in full lines in Figs. 1 and 3. During certain stages of its operation it is desired to roll, rock or tilt it either forward or 35 backward, the two extreme positions being indicated in dotted lines Fig. 1, and the extreme forward position being the one in which the molten contents of the furnace are discharged through the spout 41. It may be 40 desirable to operate the door 37 in any position of the furnace or it more often is the case that the door is not to be operated during tilting. It is therefore necessary that 45 the door-operating mechanism producing reciprocatory movement be such that this movement be transmitted to the door in practically the same proportion to the motion of the moving mechanism, for any position of the furnace. To this end there is 50 provided a stationary air or hydraulic cylinder 42 fastened to or otherwise supported by a stationary beam or girder 43, independent of the furnace. The lower end of the cylinder is connected to an actuating fluid supply pipe 44, provided with a three-way hand cock 45 within reach of the operator. The cylinder has a piston operating a piston rod 46 which has mounted on its end a cross-head 46^a carrying a rope pulley 47. Below 55 the piston and mounted on the girder or

beam 43 are two idle pulleys 48 and 49. A wire rope 50 is connected at one end to the door 37, *i. e.*, fastened in the eye 40, passes over a guide pulley 51 on the furnace frame, partially around the idle pulley 48 thence 70 over pulley 47 and the other idle pulley 49 and is fastened at the other end to an eye 52, bolt, or other equivalent device at the front of the furnace. The cross-head 46^a is connected to one end of a rope 52 that passes over a pulley 53 mounted on the beam or girder 43, so that it will be over the cylinder 42, and the other end of the rope 52 suspends a counterweight 54. Air is admitted by cock 45 through pipe 44 to the cylinder 80 beneath the piston, raises the piston, its rod, cross-head and pulley 47, thereby lengthening the distance between 47 and 48, 49. One end of rope 50 being held fast at 52, the other end connected to the door will be 85 drawn up, and with it the door 37. When the door is to be closed the cock 45 is turned to vent the cylinder and pipe 44, between the cock and cylinder, to the atmosphere, the weight of the operating parts causing 90 the piston to descend and the door to close. It will thus be seen from an inspection of Fig. 1, that the position of the pulleys 48, 49 with respect to the pulley 51 is such that the sum of the lengths of the portions of the 95 chain or rope 50 between 48 and 52, and 49 and 51 is substantially constant for any position of the furnace, consequently the door may be lifted in any position of the furnace, or the furnace may be tilted without lifting 100 the door. Any other device may be used in place of the cylinder 42 and its piston, to cause a bodily movement or lifting of the pulley 47.

We claim—

1. The combination with a furnace and tilting rockers therefor; of tilting rocking saddles on which the rockers are carried.
2. The combination with a furnace and tilting rockers therefor; of rocking saddles and rollers mounted in the saddles on which the rockers bear.
3. The combination with a furnace and rockers therefor; of a pedestal having half bearings, a pin laid in each of said bearings, substantially triangular saddles each having a half bearing at one of its apices engaging one of such pins, and flanged rollers at the other two apices of each saddle on which the rockers bear.
4. The combination with a furnace; of rockers having openings therein, beams extending through and resting in said openings, struts connecting the rockers together, structural iron supports inclined to one another and supported by said struts, and beams to support the furnace on the rockers.
5. The combination with a furnace; of a rocker having a laterally directed flange at its top on which the furnace rests and also

having openings therethrough, at least one of such rockers on each side of the furnace, structural iron beams supported by the rockers and in said openings, a strut on each side of said beams connecting the rockers together, and supports transverse of the beams and struts whereby the furnace will be supported at its sides on said rockers intermediate the rockers.

10 6. The combination with a furnace; of rockers supporting the furnace at the sides, structural iron members supported by and extending between the rockers, two bearings connected to said members, a pair of screws, a cross-head traversed by each screw, a pair of connecting rods between each cross-head, a bearing, a gear wheel on each screw, a pinion to drive each gear wheel and a synchronizing idle gear wheel gearing with both

20 pinions.

7. The combination with a furnace; of cast rockers, each composed of sections connected together and each section having an opening therein adjacent the point of connection of the sections, pads near the ends of said sections having supporting ledges, beams passing through and supported in said openings, struts connecting the pads of opposite rockers and resting on said ledges, 25 said struts inclined toward one another, and

structural iron supports transverse of the struts and beams whose tops lie in the planes of the tops of the rockers.

8. The combination with a tilting furnace, of connecting rods pivotally connected at 35 one end to the furnace, a cross head to which the other ends of said rods are pivotally connected, guides for the cross heads, a screw and driving means therefor to traverse the cross head. 40

9. The combination with a tilting furnace, of a plurality of pairs of connecting rods, pivotal connections between one end of each rod and the furnace, a cross head common to and connected to the opposite ends of 45 each pair of rods, a guide for each cross head, a screw to traverse each cross head, means to drive each screw to traverse the pertaining cross head and tilt the furnace, and equalizing means to equalize the speeds 50 of the driving means and screws.

In testimony that we claim the foregoing as our invention, we have signed our names in presence of two subscribing witnesses.
